UNITED STATES PATENT OFFICE.

HARLEY BENSKIN, OF NEWTON, IOWA.

ENGINE.

Application filed December 22, 1921. Serial No. 524,146.

To all whom it may concern:

Be it known that I, HARLEY BENSKIN, a citizen of the United States, and a resident of Newton, in the county of Jasper and State of Iowa, have invented a certain new and useful Engine, of which the following is a specification.

The object of my invention is to provide an engine of the two-cycle type, having novel features of construction.

It is well-known that the two-cycle engine is not as satisfactory as it might otherwise be on account of the fact that the fuel must be supplied during a short part of the cylinder stroke and does not have time enough to come in the desired volume or quantity and also for the reason that ordinarily the engine is fired while the fuel is not under as much compression as is desired.

It is therefore an object of my invention to provide an engine of the two-cycle type, whereby provision is made for supplying an ample amount of fuel mixture and for putting the fuel under compression at the commencement of the firing stroke of the engine.

Still a further object is to provide a novel means for handling the fuel, compressing it, and supplying it to the cylinders.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 shows a transverse, vertical sectional view through an engine embodying my invention.

Figure 2 shows a longitudinal, sectional view taken on the line 2-2 of Figure 1, through such an engine having four cylinders.

Figure 3 shows a vertical, sectional view taken on the line 3-3 of Figure 2 through the rotary fuel control valve structure, illustrating the arrangement of the spark plug and the means for scavenging any gases that might be in the spark plug or the spaces adjacent thereto.

Figure 4 shows a vertical, sectional view taken on the line 4-4 of Figure 2, embodying the details of the means for operating the compression piston; and

Figures 5, 6, 7, 8, 9 and 10 are diagrammatic views illustrating in a general way the relative positions of the explosion pistons and the compression pistons during the operation of the engine.

I will describe my engine as having four cylinders. It will, of course, be understood that the number of cylinders may be varied, as desired.

My engine is of the general type shown in Figure 1 having a body or casting indicated by the reference numeral 10, provided with one or more cylinders 11 inclined forwardly and away from the body 10 at an angle of about 30° from the perpendicular.

Opposite the cylinders 11 is a plurality of cylinders 12 inclined also at an angle of about 30° from the perpendicular and 60° from the cylinders 11.

Below the casting or engine block 10 is a lower crank case member or the like 13. The lower part of the block 10 forms the upper part of the crank case member and the block 10 and crank case member 13 are provided with opposite flanges 14 and 15, which may be locked together by bolts 16 and nuts 17.

The row of cylinders 11 is provided with an engine head 18 and the row of cylinders 12 is provided with a cover or head 19. The line of division between the engine head 18 and the engine is at the upper end of the cylinders 11. The line of juncture between the cylinders 12 and the head or cover therefore is about midway of the cylinders.

It will thus be noticed that the head 19 forms a part of the row of cylinders 12.

Suitably mounted is a crank shaft having the four cranks as shown. Connecting rods 21 are pivoted on the cranks and are connected with the respective cylinders 22 in the ordinary way.

In the head 18 and engine case or body 10 are suitable water passages 23 for water-jacketing and cooling the engine.

In the head 18 is a longitudinally extending cylindrical fuel passage or compartment 24 in which is mounted my improved rotary valve structure. My rotary valve structure is built in sections, one of which is provided for each cylinder 11. Each section comprises spaced heads 25, which are successively connected together by means of tongues 26, received in grooves 27. (Fig. 2.)

On the end of the forward valve section

25 is a beveled gear 26^a, which meshes with a beveled gear 27^a on an upright shaft 28 mounted in suitable bearings 29.

On the lower end of the shaft 28 is a beveled gear 30 meshing with a beveled gear 31 on the crank shaft. The heads 25 of each section are connected by three longitudinally extending partition or division members 32, equi-distantly spaced from each other, as illustrated for instance in Figure 1 and provided at their outer edges with curved flanges or extensions 33 arranged to fit the interior of the compartment 24 and extending in opposite directions for the respective partitions and designed to serve as valve members.

Suitably mounted in a screw-threaded opening 34 in the head 18 adjacent to and above each cylinder and slightly at one side therefrom is a spark plug 35. Each compartment 24 is connected with one of the cylinders 12 by means of a fuel passage 36. Each cylinder 12 has a passage or opening 37 communicating with the passage 36 and each compartment 24 has an opening or passage 38 communicating with a passage 36. Each cylinder 11 has an opening 39 communicating with an exhaust manifold 40. Each cylinder 12 has an opening 41 communicating with an intake manifold 42.

In each cylinder 12 is a tubular sliding sleeve 43, having on one side an extension 44 sliding in a guide 45 at the upper end of the cylinder 12. In each sleeve 43 is mounted a fuel compressor piston 46 connected in the usual way by a connecting rod 47 with one of the cranks of the crank shaft.

On each sleeve 43 is a downwardly projecting lug 48 arranged to coact with a cam 49 on the crank shaft 20. On the opposite side of each sleeve 43 is a curved arm 48^a extending to position on the opposite side of the crank shaft and adapted to coact with a cam 50 on said shaft. (Fig. 4.)

The extension 44 of the sleeve 43 has an opening 51 which is adapted in one position of the sliding movement of the sleeve 43 to register with the opening 37. The sleeve 43 is of such length in its lower position of movement, that it clears the opening 41 and closes said opening.

In each partition 32 arranged to register with the opening 34 when the rotary valve is in certain positions of its movement is a radially extended passage 52. (Fig. 3.)

The rotary valve rotates anti-clockwise from its position shown in Figure 3, and the members 33 have grooves 53 in their outer surfaces extending from the outer ends of the passages 52 a short distance along the members 33 in the direction of the advance of the valve.

I will now explain somewhat in detail the operation of my engine.

I have illustrated the engine as though the

pistons operated successively from rear to front, although in practice, I think I will arrange the pistons to operate 1, 3, 2 and 4 as to firing order, since I believe the latter arrangement gives a better balanced engine.

In Figures 5 to 10 inclusive, I have illustrated in a diagrammatic way the operation of the parts.

In Figure 5, the piston 22 is shown at 75 the upper limit of its movement. At that time the corresponding piston 46 will be in its position assumed when its crank has moved 60° away from perpendicular with relation to said piston. The sleeve 43 has 80 gone beyond its upper limit of movement and has started down, so that the upper part of the extension 44 has closed the opening 37. The firing occurs with the parts in this position.

It should perhaps be here mentioned that the figures given are for purposes of illustration and may not be exactly accurate for the best results.

Assuming that the charge in the compartment 24 above the cylinder 11 and between the partitions 32 next above the cylinder is ignited the explosion will drive the piston 22 downwardly. The pistons 22 may be cut away slightly at their upper ends, as at 54, 95 to allow the head of the piston 22 to project further into the compartment 24 for getting greater compression.

As the piston 22 is driven downwardly, it moves from position shown in Figure 5 to 100 the position shown in Figure 6 and the other parts move correspondingly as illustrated in the two figures.

The sleeve 43 and the piston 46 are then on their downward stroke. During this 105 part of the movement, any exhaust gases that may be in the opening or recess 34 pass through the passages 53 and 52 to that part of the compartment 24 which communicates with the exhaust manifold 40 for thus reducing the likelihood of injury to the spark plug. (See Fig. 3.)

In Figure 7, the piston 22 is shown two-thirds of the way down and in Figure 8, it is shown at the bottom of its stroke. When the piston 22 reaches approximately its position shown in Figure 7, the exhaust opening 39 starts to open and during the finish of the downward stroke, the exhaust opens more fully as shown in Figure 8.

When the parts are in the position shown in Figure 7, the piston 46 is at the bottom of its stroke. The sleeve 43 begins to clear the opening 41 when the firing stroke commences and leaves said opening fully open, when the firing stroke has been one-third completed, as shown in Figure 7.

When the piston 46 is in its lowermost position as shown in Figure 7, the sleeve 43 has commenced its upward stroke. As the

crank moves upwardly from its position shown in Figure 8, to its position shown in Figure 9, the sleeve 43 closes the opening 41 and the opening 51 registers with the opening 37.

The rotary valve moves to the position shown in Figure 9, where both intake and exhaust are connected with the cylinder 11, so that the inrushing gases help to scavenge 10 said cylinder.

As the stroke continues and the crank moves upwardly one-sixth of a revolution, the piston 46 forces the fuel mixture out of the cylinder 12 through the opening 37 15 and passage 36 and into the compartment 24.

It will be noted that shortly after the parts leave their position shown in Figure 9 and move toward their position shown in 20 Figure 10, the rotary valve will move to position for closing the exhaust so that the action of both pistons is such as to compress the charge in the passage 36 and the compartment 24.

When the parts reach their position shown in Figure 10, the rotary valve closes the opening 38 and the piston 22 then moves upward to its position shown in Figure 5 30 for imparting considerably greater compression to the charge above the piston head.

It will be understood that the pistons are timed and fired in proper order to secure the most desirable results.

It will be noted that by the construction 35 here provided, I have made it possible to use the incoming charge for a short time to assist in scavenging the exhaust gases.

I have provided a relatively large passage 40 through which gases may come into the explosion chamber, so that a relatively large charge may be supplied for the next explosion. This is important in a two-cycle engine, which is operative at every downward stroke of the piston. I have also provided 45 the pistons 46, which greatly assist in compressing the fuel charge and have provided the closed portion of the chamber 24 above the cylinder 11, which becomes charged with fuel already under some compression and is 50 closed while the piston 22 is one-third of its distance below its highest point, so that the final upward movement of the piston 22 imparts much greater compression to the charge.

55 The rotary valve is so arranged that it need only make one revolution for every three revolutions of the crank shaft.

It will be noted that I have provided a 60 rotary valve for controlling the fuel intake and exhaust and also for forming part of a rotary compression chamber. This structure does away with the ordinary valves and springs employed in the larger number of internal combustion engines and affords a 65 smoother working and simpler mechanism.

For the compression piston cylinder, I have used a sleeve valve structure, which is simple and effective for the purpose.

It should be noted that my rotary valve serves not only to control the ingress of fuel 70 and the outlet of exhaust gas, but that it also has chambers or compartments which serve as parts of the explosion chamber at the time of firing, and which are large enough to serve not only as fuel and exhaust 75 passages, but also as means for conveying a considerable part of the fuel and gases. These compartments or chambers are in practice of about one third the capacity of the entire firing chamber and thus a substantial part of one charge may pass into one such compartment while another charge is being fired. Also, when a filled compartment of the valve is moved to where its open end registers with the cylinder 80 the passage between the compartment and cylinder is so large that the fuel passes more quickly into the cylinder than would be possible with the valve controlled openings usually employed. This structure 85 greatly facilitates the supplying of fuel to the cylinders.

It will be understood that changes may be made in the details of the construction and arrangement of the parts of my improved engine, without departing from the real spirit and purpose of my invention and it is my intention to cover by my claims, any modified forms of structure or use of mechanical equivalents, which may be reasonably included within their scope.

I claim as my invention:

1. In an engine of the class described, having an exhaust outlet, an explosion cylinder, a fuel compression cylinder, a rotary valve structure interposed between said cylinders having a plurality of chambers of sufficient capacity for carrying a substantial part of the charge or of the exhaust gases, and means for operating said valve for bringing the chambers successively into communication with the compression chamber for taking in a substantial charge, then into simultaneous communication with the compression and explosion chambers, then to a position communicating with the explosion chamber only, then into position in communication with the explosion chamber and an exhaust outlet, then into position in communication with the exhaust outlet only.

2. In a two cycle engine, having an exhaust passage, an explosion cylinder, a compression cylinder, a rotary valve interposed between said cylinder, having three compartments of a proper size to receive a substantial charge of fuel or exhaust gases, means for rotating said valve, said parts being so arranged that each compartment successively communicates with the compres- 125 130

- 4
- sion cylinder for taking in a charge, then communicates with the compression cylinder and the explosion cylinder, then communicates with the explosion cylinder alone, then communicates with the explosion cylinder and exhaust passage, then communicates with the exhaust passage alone, and is then idle a portion of its revolution.
- 10 3. In an engine of the class described, an explosion cylinder, a compression cylinder, a rotary member interposed between said cylinders having chambers of a capacity insufficient to carry a substantial part of the charge and exhaust gases, and also to form 15 passages for affording communication between the explosion cylinder and the compression cylinder and the exhaust opening in different positions of the rotation of said member, said chamber in rotary member being adapted to form substantial parts of the explosion chamber at the time of firing, the explosion cylinder having a piston arranged to project into the chamber in the rotary member for increasing the compression of 25 the fuel just before firing.

Des Moines, Iowa, December 16, 1921.
HARLEY BENSKIN.
